UNITED STATES PATENT OFFICE.

ALFRED ELTEN, JR., OF RAUXEL, GERMANY.

VEHICLE-WHEEL.

1,371,551.

Specification of Letters Patent. Patented Mar. 15, 1921.

Application filed May 1, 1915. Serial No. 25,242.

To all whom it may concern:

Be it known that I, ALFRED ELTEN, Jr., a citizen of the United States, at present residing at Rauxel, in the Province of Westphalia, Empire of Germany, have invented certain new and useful Improvements in Vehicle-Wheels; and I do hereby declare that the following is a full, clear, and exact description of the invention, such as will enable others skilled in the art to which it appertains to make and use the same, reference being had to the accompanying drawings, forming part of this specification.

This invention relates to resilient wheels of the class in which the stresses on the hub are yieldingly transmitted to the tire-rim, or vice versa, through carrying members and intermediate, revolute spacing members, that translate any motion of the tire-rim in relation to the hub in the plane of the wheel, caused by such stresses, into a corresponding motion, at right angles to the plane of the wheel, of part of the carrying members, thereby varying the distance between the carrying members, against the resistance of resilient means.

The present invention consists in the provision of spacing members that tilt laterally while being subjected to the pressure of the stresses from the one side and to the counter-pressure of the resilient means from the opposite side, whenever the stresses on the wheel increase and thereby force the carrying members with the supporting abutments for the spacing members, against the appropriately increasing resistance or pressure of resilient means, obliquely farther apart in such a manner, that, for a uniform increase of eccentricity of hub and tire-rim, the distances separating the carrying members increase at a decreasing rate, while the pressures increase at an increasing rate. The tilting spacing members are maintained in operative engagement with the carrying members by the two opposing pressures that act toward each other and toward the middle of the spacing members.

The object of the invention is, to provide a wheel in which the resilient resistance to the motion of the hub, relative to the tire-rim due to the *vis viva* of the load, increases at a correspondingly increasing rate.

One embodiment of the present invention

is disclosed in the structure illustrated in the accompanying drawings, in which:

Fig. 1 is a side view of a portion of a closed, unweighted wheel,

Fig. 2 is a similar view of a weighted wheel of modified form,

Fig. 3 an enlarged view of the connection of the hub with the resilient carrying members of the wheel,

Fig. 4 an enlarged section on line A—A of Fig. 1,

Fig. 5 an enlarged section on line B—B of Fig. 1,

Fig. 6 an enlarged section on line C—C of Fig. 2,

Fig. 7 an enlarged section on line D—D of Fig. 2, and

Fig. 8 is a theoretical diagram.

The new construction consists of the hub *a* having projections *b* that engage with the serrations *c* and *d* of the resilient carrying members *e* and *f* that are adjustably pressed toward the middle plane of the wheel by the bolts *g* and the rings *h* and *i* and thus are immovably held on the hub.

The tire *j* is mounted on the rim or felly consisting of the rings *k* and *l* and the carrying member *m*, that are secured together by rivets *n*. The carrying member *m* is provided with perforations or projections *o* through or around which the mass of the tire is formed, as well as with circular grooves or "runways" *p* and *q* which, with the corresponding circular grooves or runways *r* and *s* on opposite parts of the resilient carrying members *e* and *f*, form the supporting abutments for the circular "running edges" *t*, *u*, and *v*, *w* of the tilting, revolute spacing members *x* and *y*.

As shown in Fig. 2, the resilient sides or carrying members *e* and *f* may be provided with perforations *z*, or the like, to form spokes.

In carrying my invention into practice, I preferably arrange the spacing members *x* and *y* in the form of angularly revolute bodies, the running edges *t*, *u*, and *v*, *w*, or equivalent bearing parts of which are situated in parallel, co-axial, sectional planes of an imaginary ellipsoid of rotation, or like body. Such a spacing member may be termed a double or twin rotor whose two parallel running edges contact the runways

in two opposite supporting abutments and thus support the load, at diagonally opposite places, transmitting the stresses from the runway on one carrying member to the runway on the opposite carrying member. In the concentric condition of the wheel, these running edges rest fully in corresponding circular channels p, q and r, s , or equivalent bearing parts, of substantially the same diameter, that form the supporting abutments on the carrying members e, f and m , see Figs. 1, 4 and 5.

When the wheel is dynamically or additionally stressed and the tire-*rim*, in moving relative to the hub in the plane of the wheel, becomes more or less eccentric to it, the spacing members tilt correspondingly and simultaneously assume uniformly oblique positions relative to their supports and to the plane of the wheel; so to speak, stand on edge, revolving angularly on their running edges, at diagonally opposite points, in the supporting abutments, around their center of gravity, with a rolling motion when the wheel revolves, see Figs. 2, 6 and 7.

In the theoretical diagram, Fig. 8, E denotes the diagonal, or line of action, of the spacing members and α the angle formed by the diagonal with the plane of the wheel. F signifies the distance separating the abutments, G the weight or stress borne by the spacing members, H the resulting lateral pressure exerted by the spacing members against their supporting abutments on the carrying members and I the counterpressure of the resisting, resilient means.

Should the spacing members, due to additional stresses, tilt from their concentric positions α' and move through different degrees of eccentricity, as indicated by scale I, to position α'' , then the distance F between the supporting abutments of the spacing members increases at a decreasing rate, as indicated by scale II; or, to be more precise, the distances increase as the sine of the different angles formed by the diagonal E of the spacing members with the plane of the wheel, while the corresponding pres-

sures H increase as the tangents of these angles.

50

Thus:—

$$F = E \sin \alpha, \text{ and } H = \frac{G}{2} \tan \alpha.$$

The characteristic action of these novel spacing members is, to enable the resilient resistance within the wheel to any motion of the hub, relative to the tire due to the *vis viva* of the load, to be very slight when the wheel passes over slight obstacles, insuring exceedingly comfortable riding, but to effectively counteract violent shocks through a comparatively very great resilient resistance. In other words, the resilient resistance to shocks may increase in this wheel at 65 a most appropriately and efficiently increasing rate.

What I claim as new is:—

A vehicle wheel comprising hub and rim portions normally substantially concentric and capable of relative eccentric movement under varying load and shock, circular series of opposed circular abutments carried by the hub and rim portions respectively, and tilting thrust members interposed between said seats to separate the same against resilient resistance, said thrust members having double circular edges whereon they tilt in the circular seats under load or shock, so as to assume uniformly oblique positions relative to their seats and to the plane of the wheel, pivoting and rolling on their running edges at diagonally opposite points in the seats in like manner as the wheel revolves, the seats being thereby separated by 85 pressures increasing at an increasing rate applied simultaneously at a plurality of points around the axis.

In testimony whereof I have hereunto set my hand in presence of two subscribing witnesses.

ALFRED ELTEN, JUN. [I.S.]
